UNITED STATES PATENT OFFICE.

LOUIS WEIDLICH, OF STRATFORD, CONNECTICUT.

ADJUSTABLE REFLECTOR FOR INCANDESCENT LAMPS.

1,152,581.

Specification of Letters Patent.

Patented Sept. 7, 1915.

Application filed February 23, 1915. Serial No. 8,940.

To all whom it may concern:

Be it known that I, LOUIS WEIDLICH, a citizen of the United States, residing at Stratford, county of Fairfield, State of Connecticut, have invented an Improvement in Adjustable Reflectors for Incandescent Lamps, of which the following is a specification.

This invention has for its object to provide a simple and inexpensive universally adjustable reflector for incandescent lamps which may be easily attached and detached and may be locked securely in any position relatively to the lamp, in which it may be placed.

With this end in view I have devised the novel reflector which I will now describe, referring to the accompanying drawing forming a part of this specification and using reference characters to indicate the several parts.

Figures 1 and 2 are views partly in elevation and partly in section illustrating the application of my novel reflector to the bulb of an incandescent lamp and showing different adjustments of the reflector relatively to the lamp.

My novel structure comprises a coil spring of special construction and clamping means for adjustably securing the spring to the reflector.

10 denotes the bulb of an incandescent lamp, and 11 a reflector which may be of any ordinary or preferred shape or design.

My novel spring comprises two holding coils, indicated by 13, which are connected by a central coil 14 of greater radius than the holding coils, the purpose of which will presently be explained.

The clamping member comprises a stud 15 which is provided near one end with a transverse hole through which the spring is passed and is threaded at the other end, a sleeve 16 upon the stud within the reflector and an ornamental nut 17 outside the reflector which engages the thread.

In assembling, the spring is passed through the hole in the stud until the stud is approximately at the middle of the central section, then the sleeve is placed over the stud, then the stud is passed through a central hole in the reflector from the inner side and then the nut is turned onto the stud to

lock the parts in place. The sleeve is shown as provided with a transverse groove 18 in one end to receive the central section of the spring. This groove is not essential however to the operativeness of the structure. The coils of the spring are made of sufficient size to yieldingly receive the bulb of the lamp between them and to receive within their peripheries sufficient of the curved cheeks of the bulb to retain the structure as a whole securely in place through such engagement. By providing the spring with a central coil of greater radius than the holding coils, I carry the point of attachment of the spring to the stud entirely outside the path of movement of the seat 12 at the end of the lamp bulb in shifting the position of the reflector, as from the position shown in Fig. 1 to that shown in Fig. 2.

It will be readily understood that within the sphere of movement permitted by the size of the reflector there is no limit to the universality of the adjustment. The coils will slide freely over the surface of the bulb in placing the reflector in any required position, while the slight grip of the coils upon the lamp bulb is sufficient to retain the reflector in any position in which it may be placed. By slightly loosening the nut, the central coil may be either oscillated in the stud or moved longitudinally therein.

Having thus described my invention I claim:

A device of the character described comprising a reflector, holding coils adapted to yieldingly engage the bulb of an incandescent lamp, a central coil continuous with and connecting the holding coils and of greater radius than said coils, a stud through which the central coil passes, a sleeve between the central coil and the reflector, and a nut on the stud for locking the parts in place, loosening of said nut permitting either oscillation or longitudinal movement of the central coil relatively to the stud.

In testimony whereof I affix my signature in presence of two witnesses.

LOUIS WEIDLICH.

Witnesses:

H. W. MEADE,
E. M. CULVER.
